(57) **CLAIM**

The ornamental design of the trike caddy, as shown and described.

DESCRIPTION

FIG. 1 is a top perspective view of the trike caddy, showing my new design.

FIG. 2 is a front elevational view thereof.

FIG. 3 is a rear devotional view thereof.

FIG. 4 is an elevational right side view thereof.

FIG. 5 is an elevational left side view thereof.

FIG. 6 is a top plan view thereof.

FIG. 7 is a bottom view thereof; and,

FIG. 8 is a bottom perspective view of the trike caddy, showing my new design.

The broken lines in the drawings depict portions of the Trike Caddy that form no part of the claimed design.
